UNITED STATES PATENT OFFICE.

HERMAN S. GRABER, OF ST. LOUIS, MISSOURI.

WATER-GAGE.

SPECIFICATION forming part of Letters Patent No. 665,209, dated January 1, 1901.

Application filed July 2, 1900. Serial No. 22,327. (No model.)

To all whom it may concern:

Be it known that I, HERMAN S. GRABER, a citizen of the United States, residing at St. Louis, in the State of Missouri, have invented 5 a new and useful Improvement in Water-Gages, of which the following is a specification.

My invention relates to a water-gage for steam-boilers and is in the nature of an improvement on the invention for which I obtained Letters Patent in the United States, 10 dated January 10, 1893, No. 489,804, for an improvement in water-gages, in which the valve of the upper and lower portions, respectively, of the water-gage operates automatic- 15 ally and is connected with a rock-shaft having an arm or handle outside the valve-casing, whereby the valve is operated by hand and its position indicated at all times.

My invention has for its object to prevent 20 corrosion and sticking of the valves and their operating parts, and thereby to insure a positive automatic closing of the valves in case of breakage of the gage-glass and to enable the valves to be freely moved by hand when 25 desired.

It consists in features of novelty as herein-after described and claimed, reference being had to the accompanying drawings, forming part of this specification, whereon—

30 Figure 1 is a vertical longitudinal section through the upper portion or valve-casing of my improved water-gage on line 1 1 in Fig. 3, showing the valve, with its stem, in side elevation and in the open position; Fig. 2, a similar view to Fig. 1 with the valve closed; Fig. 3, a vertical transverse section through the casing on line 3 3 in Fig. 1; Figs. 4 and 5, vertical transverse sections on lines 4 4 and 5 5, respectively, in Fig. 3; Fig. 6, a side view of 35 the water-gage with its parts assembled and applied to the shell of a steam-boiler, the shell being in section, broken away. Fig. 7 is a corresponding view to Fig. 1 of the casing to reduced scale, broken away, showing a modification of my invention; and Fig. 8, a vertical section through the gland and stuffing-box for the gage-glass in the lower portion or casing (broken away) of the water-gage, showing part of my invention relating to the gage-glass.

Like letters and numerals of reference denote like parts in all the figures.

a a' represent the upper and lower portions or valve-casings, respectively, and *b* the gage-glass, of my improved water-gage, which is applied to the boiler *c* in the usual manner.

Referring particularly to the upper portion or valve-casing *a*, *d* represents the valve, which in the normal operation of the water-gage is open, as shown in Figs. 1 and 6, so as to allow 60 the steam from the boiler *c* to pass around the valve *d* through the open end of the passage 1, which projects into the boiler *c*, and thence through the enlarged chamber 2 of the casing *a* into the upper part of the gage- 65 glass *b*, as in the ordinary gage.

The valve *d* is preferably circular, having on one side a correspondingly-shaped flat-faced projecting disk 3, composed of rubber composition or other suitable packing material and adapted for closing against the valve-seat *d'*, which surrounds the opening of the passage 1.

To the valve *d* is fixed a stem 4, which extends longitudinally through the passage 1 75 and enlarged chamber 2 of the casing *a* and is supported at its free end opposite to the valve *d* in a guide or cylindrical recess 5, formed, preferably, in the screw-plug 6, which closes an opening 6' through the front wall of 80 the casing *a*, as shown.

The stem 4 is preferably spiral-shaped circumferentially for a suitable portion of its length within the passage 1 of the casing *a*, as shown, so that on opening the usual blow-out cock or on the breakage of the gage-glass *b* the valve *d*, with its stem 4, will be rotated by the sudden rush of steam (or water) from the boiler *c* during the consequent closing of the valve *d* onto its seat *d'*, and thereby remove any deposit of scale or sediment and prevent corrosion and sticking of the parts.

On the stem 4, preferably on that part within the enlarged chamber 2 of the casing *a*, are formed circumferentially two opposite collars 95 or shoulders 7, between which the valve *d*, with its stem 4, is engaged by a forked tappet, hereinafter more particularly referred to.

Below the stem 4 of the valve *d* is mounted a rock-shaft *e*, which preferably extends across 100 the enlarged chamber 2 of the casing *a*. The rock-shaft *e* has its bearing at one end within a cylindrical recess 8 formed in one of the side walls of the casing *a* and toward its other

end in a stuffing-box *f*, containing a specially-arranged packing device, as hereinafter described, which is held in the stuffing-box *f* by the gland *f'*, through which the rock-shaft *e* projects beyond the outside of the casing *a*.

The rock-shaft *e* within the casing *a* is formed with a square-shaped portion *9*, which fits in a correspondingly-shaped hole formed through the hub of a forked tappet *g*, the fork of which straddles and engages the stem *4* of the valve *d* between its collars or shoulders *7*, as before mentioned, the said fork closely hugging the collars or shoulders *7*, so that on a partial rotation of the rock-shaft *e* and consequent vibration of the tappet *g* in one direction the stem *4* of the valve *d* will be moved longitudinally, so as to open the valve *d* from its seat *d'* and admit steam from the boiler *c* into the passage *1*, as shown in Figs. 1 and 6, and when moved in the opposite direction so as to close the valve *d* onto its seat *d'* and shut off the steam from the passage *1* and casing *a*.

On the rock-shaft *e*, outside the casing *a*, is fixed an arm or handle *h*, by which the rock-shaft *e* is operated by hand and which when the valve *d* is open, as shown in Figs. 1 and 6, is preferably arranged in the vertical position, and when the valve *d* is closed on its seat *d'*, as seen in Fig. 2, the arm *h* will assume an inclined position, as indicated by dotted lines in Figs. 2 and 6.

On the rock-shaft *e* is fixed conjointly with or in proximity to the handle *h* a second arm *i*, which is arranged at a suitable angle to the arm *h*, and from the arm *i* extends a cord *10*, by which the arm *i* can be pulled downward and the rock-shaft *e* operated by hand at any desired distance from the water-gage.

For preventing the corrosion and sticking of the rock-shaft *e* and so enabling it to be freely turned at all times with the least amount of friction the rock-shaft *e* where it passes through the stuffing-box *f* and gland *f'* is formed at the inside of the casing *a* with a circular collar *11*, which bears against the exposed face of a circular ring *12*, composed of rubber composition or other suitable material and located within the stuffing-box *f*. The rock-shaft *e* passes through but is out of contact circumferentially with the ring *12*, the gland *f*, which surrounds but is out of contact with the rock-shaft *e* thereat, being screwed (or otherwise adjusted) into the stuffing-box *f*, so as to securely hold the disk *12* in place against the inner shoulder *13* of the stuffing-box *f*, the shoulder *13* surrounding but being clear of the periphery of the collar *11*, which bears against the ring *12* thereat, as before named.

In the end of the rock-shaft *e*, having its bearing in the recess *8* of the casing *a*, is formed a socket *14*, within which is fixed one end of a spiral spring *15*, the other end of the spring *15* bearing against the closed end of the recess *8*, whereby owing to the resilience of the spring *15* the rock-shaft *e* is normally

constrained endwise, so as to maintain a positive and constant pressure of the collar *11* against the ring *12*. By this arrangement the rock-shaft *e* being out of contact circumferentially with the ring *12* and its collar *11* being in steam-tight contact with the exposed face of the ring *12*, steam or fluid is prevented from passing from the steam chamber or casing *a* through the ring *12* into the stuffing-box *f*, whereby the rock-shaft or spindle *e* can be easily turned, and the corrosion and sticking thereof owing to the escape of steam into the stuffing-box in the ordinary arrangement of packing are obviated.

The end or bearing portion of the rock-shaft *e* within the recess *8* is of a flattened circular form circumferentially, forming spaces between the rock-shaft *e* and the surrounding wall of the recess *8*, so as to allow the free circulation of the steam (or water) therethrough to and from the recess *8* beyond the end of the rock-shaft *e*. By this arrangement the scale or sediment is prevented from entering the stuffing-box *f*, and the friction of the parts being reduced to a minimum the movement of the rock-shaft *e* is readily effected either automatically by the valve *d* or by the arm or handle *h*, as the case may be. By this arrangement also on removing the gland *f'* from the stuffing-box *f* the rock-shaft *e*, with the ring *12*, can be withdrawn from the casing *a* and tappet *g* for renewing the ring *12* or for cleaning purposes without the use of a removable screw-plug in the opposite side wall of the casing *a*.

In the operation of my improved water-gage corrosion of the parts and deposit of sediment are prevented by the automatic rotation of the valve *d* when blowing out, and this feature, combined with the practically frictionless and easy movement of the rock-shaft *e* and other parts connecting with the valve *d*, insures a positive automatic closing of the valve *d* onto its seat *d'* in case of breakage of the gage-glass *b*, the position of the valve *d* in such case being at once indicated by the arms *h* and *i*. Moreover, by the automatic cleaning and sensitiveness of the device the efficiency and reliability of the water-gage for indicating the true level of the water in the boiler are increased.

The lower portion or valve-casing *a'* of the water-gage is identical in every respect to the upper portion or casing *a* above described, excepting that the lower portion *a'* is provided on its under side with the discharge-pipe *17*, (shown broken away in Fig. 6,) which may be directed to any convenient part of the boiler-house and is provided with a blow-out cock or valve *k*, which may be located and operated where required.

For preventing the breakage of the gage-glass *b*, which frequently occurs when inserting it into the stuffing-box *18* in the lower portion or casing *a'*, owing to the unevenness of the lower edge of the gage-glass *b* bearing directly on the bottom shoulder *19* of the stuff-

ing-box 18, a ring 20, composed of metal, rubber, or other suitable material, is interposed between the shoulder 19 and the end of the gage-glass *b*, whereby when the latter is rotated, owing to the screwing home of the gland 21 and consequent compression of the rubber packing-ring 22 against the glass *b*, the ring 20 is rotated with the glass *b*, whereby the lower edge of the glass *b* is prevented from 10 contact with and grinding on the shoulder 19 and its breakage avoided.

In the modification of my invention, as shown in Fig. 7, a hinged swing-valve *l* is used in lieu of the valve *d*, with its stem 4, as above described, in which case the forked tappet *g'* is connected with the valve *l* by a pin 23, which connects the two arms of the tappet *g'*, fixed on the rock-shaft *e*, and engages in a yoke or stem 24, formed on the under side of the valve *l*, whereby the valve *l* is automatically closed onto its seat *l'* and opened by the arm *h* on the rock-shaft *e* outside the casing *a* in a similar manner to the valve *d* before described.

What I claim as my invention, and desire 25 to secure by Letters Patent, is—

1. In a water-gage for a steam-boiler, the combination of a valve, opening from the valve-casing into the boiler, and having its stem adapted to be engaged within the said 30 casing by a tappet held on a rock-shaft, the said shaft projecting at one end through a stuffing-box, and having a collar within the said casing bearing against the exposed face

of a packing disk or ring contained in the stuffing-box, a spring bearing against the opposite end of the rock-shaft, and an arm fixed on the said shaft outside the casing, substantially as described. 35

2. In a water-gage for a steam-boiler, the combination of a valve, opening from the 40 valve-casing into the boiler, and having its stem adapted to be engaged within the said casing by a tappet held on a rock-shaft, the said shaft projecting at one end through a stuffing-box, and having a collar within the 45 casing bearing against the exposed face of a packing disk or ring contained in the stuffing-box, a spring bearing against the opposite end of the rock-shaft, and an arm fixed on the said shaft outside the casing, the said valve-stem 50 having a spiral circumferential portion, substantially as described.

3. A rock-shaft or spindle mounted within a steam chamber or casing and projecting through a stuffing-box and gland, and through 55 a ring held within the stuffing-box by the gland, the said shaft being out of contact circumferentially with the ring and having a collar adapted to bear steam-tight against the exposed face of the said ring within the casing, substantially as shown and for the purpose described. 60
